HINGED POLE CONNECTOR

Kenneth C. Jenne, Lake Worth, Fla., assignor to Malleable Iron Fittings Company, Branford, Conn., a corporation of Connecticut

Original No. 2,825,943, dated Mar. 11, 1958, Ser. No. 629,704, Dec. 20, 1956. Application for reissue Dec. 21, 1959, Ser. No. 861,165

4 Claims. (Cl. 20—92)

Matter enclosed in heavy brackets **1** appears in the original patent but forms no part of this reissue specification; matter printed in italics indicates the additions made by reissue.

The present invention relates to an improved hinged pole connector, particularly for timber structures formed of round wood poles, and has for an object to provide a connector for attachment whereby a pair of round wood poles may be secured in any desired angular relation with the axes of the poles lying within a common plane. The hinged connection according to the invention comprises a pair of hinged members, and it is an object of a preferred embodiment of the invention to provide a connection in which the two members are of identical form.

A further object is to provide flange means upon the connector members, so arranged that the flange means of one member of the hinge connection will interengage the flange means of the other member of the connection in such relation that the poles connected to the two members will be disposed with their axes in a common plane.

Other objects and advantages of the invention will become apparent from a consideration of the following detailed description taken in connection with the accompanying drawing wherein a satisfactory embodiment of the invention is shown. However, it will be understood that the invention is not limited to the details disclosed but includes all such variations and modifications as fall within the spirit of the invention and the scope of the appended claims.

In the drawings:

FIG. 1 is a top plan view of a hinged connector member according to the invention;

FIG. 2 is a side elevation, partially in central longitudinal section;

FIG. 3 is a rear elevation showing the pole engaging side of the member;

FIG. 4 is an end elevation;

FIG. 5 is a side elevation showing the two identical members of the hinged connection connected together and disposed in angular relation;

FIG. 6 is an end view of the members as seen in FIG. 5, a pole being shown connected to one of the members; **1** and **2**

FIG. 7 is a side elevation showing an alternative method of connecting the two members of the hinged connection **1**;

FIG. 8 is an end view similar to FIG. 6 and showing a pair of poles connected by the hinged connector; and

FIG. 9 is a side elevation partially in vertical section taken along the line 9—9 of FIG. 8.

Referring to the drawing, the hinged connector member, indicated generally as **10**, comprises a base portion **11** having a forward side and a rearward side or inner face **12** which is concavely curved at its intermediate portion **11** to substantially embrace the convex curved surface of a pole, being provided adjacent each end with a series of transverse ribs **13** and projecting spurs **14**. The curvature of the intermediate portion of the face **12** is substantially cylindrical, with its radius center substantially coinciding with the diametric plane of the pole **27** with which the connector member is to be connected, as

2

seen in FIG. 6. Centrally of the base there is provided a bolt-receiving hole **15** having its axis substantially coincident to the radius of the curved face **12** and to the axis of the through bolt **28** extending diametrically through the pole, and adjacent each end there is provided a slot **16** which may be either engaged by a bolt or by a lag screw for fastening the end portions of the connector to the pole.

At the forward side of the base there is provided a bearing projection **17** provided with a pair of projecting lugs **18**—**18** for the purpose of preventing turning of a bolt head or nut engaged with the bearing surface **17**. Projecting bearing portions **19** surround the slots **16** to form bearings for the heads of bolts or lag screws engaged through the slots. Transverse reinforcing ribs **20** extend between the sides of the bearing portions **17** and **19** and a pair of flanges **21** and **22** projecting forwardly from the base **11**.

The flange **21** is provided in flush relation with one longitudinal edge of the base, while the flange **22** is inwardly offset from the other longitudinal edge a distance substantially equal to the thickness of the flange **21**, so that when one connector member is interengaged with another identical connector member, as shown in FIGS. 5-7, the flange **21** of one connector member will be adjacent the outer side of the flange **22** of the other connector member and its outer surface will be substantially flush with the adjacent edge of the base portion **11**. The flanges are provided at suitable points with axially aligned bolt-receiving holes **23**—**23** and **24**—**24**, the holes **23**—**23** having their axis intersected by the axis of **1** being aligned with the centrally disposed bolt-receiving hole **15** while the holes **24**—**24** are disposed relatively close to one end of the connector member. The edges of the flanges are cut away, as at **25**—**25**, between the centrally disposed holes **23** and the end of the member opposite from the end contiguous to the holes **24**—**24**.

The two members of the hinged connector are adapted to be hingedly connected by a hinge bolt **26**, as shown in FIGS. 5-7, and in certain installations it is preferred that this bolt be engaged through the holes **24** adjacent one end of the members. In other installations it is preferred that the axis of the hinge bolt **26** be intersected by the axes of the through **1** hinged connection be substantially in line with the bolts connecting the members to the poles, and in such case the hinge bolt is engaged through the holes **23**, as seen in FIG. 7. In this case the clearance provided by the cutaway portions **25** permit maximum angular hinge movement of one member relative to the other. The predetermined relationship of the flanges **21** and **22** to the bolt-receiving hole **15** is such that the interengagement of the flanges of the two members of the hinged connection disposes the axes of the holes in a common plane normal to the axis of the hinge bolt **26**.

In FIG. 6 one **1** pole **27** of a pair of poles is shown secured to one of the connector members by a through bolt **28** extending diametrically through the pole having its head end which projects from the pole engaged upon the bearing projection **17** between the lugs **18**—**18**. The pole is additionally secured by lag screws **29** engaged through the slots **16**. The other pole **27** is connected in similar manner to the other connector member as shown in FIGS. 8 and 9. The positioning of the poles is such, through their seating engagement with the curved inner faces **12** and their retention by the diametrically extending through bolts secured in the holes **15**, that the axes of the through bolts are disposed in a common plane normal to the axis of the hinge bolt **26**.

What is claimed is:

1. A hinged pole connector for hingedly connecting round wood poles, comprising a pair of identical hinge

members, each of said hinge members consisting of a base portion having a forward side and a rearward side, said rearward side being concavely curved for substantially conforming engagement with the round surface of a pole, said base portion having a bolt receiving passage having its axis substantially coincident to the radius of said concavely curved rearward surface to receive a bolt extending diametrically through a pole engaged by said concavely curved rearward surface, a pair of flanges projecting from the forward side of said base portion each having a predetermined wall thickness, and one of said flanges being inwardly offset with respect to said bolt receiving passage a distance substantially corresponding to said wall thickness, and said flanges having axially aligned hinge bolt receiving holes, said hinge members being interengaged with the inwardly offset flange of each of said members in engagement at its outer side with the inner side of the non-inwardly offset flange of the other member, and a hinge bolt engaged through the bolt receiving holes of said interengaged flanges and hingedly connecting said members together.

2. A hinged pole connector according to claim 1, further characterized in that the flanges of each of said hinge

members has axially aligned bolt receiving holes intersected by the axis of said bolt receiving passage.

3. A hinged pole connector according to claim 2, wherein in said flanges each have additional hinge bolt receiving holes spaced from said hinged bolt receiving holes intersected by the axis of said bolt receiving passage.

5 4. A hinged pole connector according to claim 3, wherein said flanges have cutaway edges at one side of said hinge bolt receiving holes.
